UNITED STATES PATENT OFFICE.

DANIEL O. SNYDER, OF MUNCY, PENNSYLVANIA.

METAL RAILWAY TIE.

Application filed November 3, 1927. Serial No. 231,880.

This invention relates to an improved metal railway tie, constructed to accommodate special rail fastening devices such as are employed for connecting the rails to the tie.

5 The invention herein disclosed is an improvement upon my prior Patent, No. 1,525,311 granted to me under date of February 3, 1925.

10 As in the patented case, the invention here, also relies for its distinctiveness upon the utilization of novel cushioning means between the rail ties and the rails.

15 The particular details forming the alleged new re-organization of parts will become more readily apparent from the following description and drawings.

In the drawings:—

Figure 1 is a top plan view of the rails, and 20 one of the ties showing the improved fastening means.

Fig. 2 is a side view of the same, with a portion of the tie broken away and shown in section.

Fig. 3 is a longitudinal section taken on 25 the line 3—3 of Fig. 1.

Fig. 4 is a perspective view of a retaining wedge.

Fig. 5 is a perspective view of a plate adapted for disposition between the cushioning blocks and the base of the rail.

30 Fig. 6 is a perspective view of one of the cushions.

Fig. 7 is a perspective view of a rail retaining plate for cooperation with said cushion.

Fig. 8 is a slightly modified type of retaining wedge.

Attention is invited to Figs. 1 to 8 inclusive. As shown here, and as particularly detailed in Fig. 4, the reference character 12 designates a hollow steel tie, which, as shown in Fig. 2, is provided with transverse reinforcing members 13. Also at each end, it is formed with elongated rectangular openings 14 across which the rail 15 extends. The rail is of course of ordinary construction.

Interposed between the rail and the tie, is a special cushioning member in the form of a wooden block, generally designated at 16 in Fig. 6. This comprises a central elevated portion 17 on which the rail rests, and an outstanding flanged portion 18 which rests upon the tie, and is fastened thereto by metal retaining plates 19. These retaining plates are of generally L-shaped configuration as shown in Fig. 1 and have channel forming

portions into which the flanged marginal portions of the blocks are slipped.

After the block is slipped into the channels, retaining tongues at the open ends of 60 the channels are designated at 20 in Fig. 1, and are bent down to hold the blocks in place. The block is formed on opposite sides with notches 21, through which the upstanding portions 22 and 23 of a retention clamp 24 extend. The proportions of these parts 22 and 65 23 with respect to the block are brought out clearly in Fig. 3.

From the last-named figure, it will be seen that the portion 22 is provided at its upper 70 end with a laterally directed finger 25, which extends over the base of the rail, while the portion 23 is formed with a notch 26 for reception of a removable retaining wedge 27 of the form represented either in Fig. 4 or 75 Fig. 8 as is required.

In either instance, the wedge is formed with a split retaining finger 28 which can be bent to the dotted line position to hold the wedge in place, as shown for instance in Fig. 80 1. Preferably, a seat plate 29 (see Fig. 5) is provided, this being placed on the top of the raised portion 17 of the cushion block and having an upstanding flange 30, engaging the base flange of the rail as shown in Fig. 3, and 85 a depending flange 31, bearing against the cushion blocks.

It will thus be seen that I have evolved a structure which comprises a solid tie across which the wooden block extends, this block 90 being constructed to accommodate the arm portions of the retaining clamp 24. The retaining clamp engages the base flange of the rail as shown in Fig. 3. The block is held in place by removable metal clips and the clamp- 95 ing device extends up thru the slot 14 in the tie. In this way, the rail is firmly clamped against the metal seat plate, resting on a cushioning block, and the block is in turn anchored upon the web portion of a hollow steel tie. Thus the connection is firm and secure, and is of a yieldable nature.

Having thus described my invention, what I claim as new is:—

1. In a railway structure of the class described, a hollow sheet metal tie provided with an elongated opening, a cushioning block extending transversely across the tie and opening, means for fastening said block to the tie, a rail resting on said cushioning means, and a rail clamp for fastening the rail to the cushioning means, said rail clamp having por- 105 110

tions extending up through the opening in said tie.

2. In a railway structure of the class described, a sheet metal rail tie of channel-shaped cross section, the web portion of the tie being formed with an elongated opening, a cushioning block extending transversely across the tie and said opening, retainers for said block attached thereto and to said tie, 10 a substantially U-shaped rail fastening, a rail resting upon said cushioning block, said rail fastening being disposed in said opening, and having the upstanding arm portions thereof projecting upwardly above the block and fastened to the base flange of the rail.

3. In a construction of the class described, a metal rail tie of channel-shaped cross section provided adjacent one end with an elongated opening, a wooden block extending 20 transversely across the tie and across said opening, said block including a central raised portion and a flanged base portion, the flanges being formed on opposite sides with notches, metal clips fastened to the flanged portions 25 of the block and also fastened to the tie and holding the block on the tie, a rail resting on the raised portion of the block, and means fas-

tening the rail to the block comprising a clamp having arm portions extending upwardly along the sides of the block and 30 through said notches.

4. In a construction of the class described, a metal rail tie of channel-shaped cross section, provided adjacent one end with an elongated opening, a wooden block extending 35 transversely across the tie and across the said opening, said block including a central raised portion and a flanged base portion, the flanges being formed on opposite sides with notches, metal clips fastened to the flanged portions of the block and also fastened to the tie and holding the block on the tie, a rail resting on the raised portion of the block, means fastening the rail to the block comprising a clamp having arm portions extending upwardly 40 along the sides of the block and through said notches, a seat plate interposed between the base of the rail and said raised portion of the block, said plate having laterally directed 45 edge flanges cooperating with the rails and blocks respectively.

In testimony whereof I affix my signature.

DANIEL O. SNYDER.
